UNITED STATES PATENT OFFICE.

JAMES ROBERT CRUIKSHANK, OF VANCOUVER, BRITISH COLUMBIA, CANADA.

ROTARY TOOTHBRUSH.

Application filed October 5, 1922. Serial No. 592,654.

To all whom it may concern:

Be it known that I, JAMES ROBERT CRUIKSHANK, a subject of the King of Great Britain, residing at the city of Vancouver, in the Province of British Columbia, Canada, have invented certain new and useful Improvements in Rotary Toothbrushes, of which the following is a specification.

My invention relates to improvements in rotary toothbrushes, and the object of my invention is to provide a brush of this character which is of the simplest construction and capable of being manufactured and sold at a low cost without impairing or detracting from its efficiency.

I attain this object by the construction illustrated in the accompanying drawings in which—

Fig. 1 is an outside view of the toothbrush.

Fig. 2 is an outside view showing the cap removed and operating handle extended.

Fig. 3 is a longitudinal sectional view.

Fig. 4 is a cross sectional view of the cap taken through the line 4—4 of Fig. 1.

Fig. 5 is an enlarged detail view of the socketed member and associated parts.

Fig. 6 is a cross sectional view taken through the line 6—6 of Fig. 5.

Fig. 7 is a detail view of the socketed member.

Fig. 8 is a fragmentary detail view of the inner end of the spiral operating member.

Similar figures of reference indicate similar parts throughout the several views.

The device consists of a tubular member 1 of suitable diameter and length open at both ends, and the bore 2 of which is parallel throughout its length, the bore being reduced in diameter in close proximity to its right hand end, as at 3, by depressing an annular groove 4 in the tube wall. Towards its opposite or left hand end the tube is depressed as at 5 to provide an internal projection 6 on one side and directly opposite this projection is a semi-circular slot 7 cut in the tube, as shown more particularly in Fig. 5. Freely mounted in the left hand end of the bore 2 is a socketed member 8 having a concentric socket 9 adapted to receive tightly when pressed thereinto the inner end of the brush head stem 10, which stem may be formed of any suitable material and length and which is rotatably

supported at its opposite, or outer, end in a bearing 11 formed in the outer end of a guard 12 suitably shaped to comfortably protect the mouth wall from the brush while rotating. The guard 12 where it extends over the brush is formed concavo-convex both longitudinally and transversely and terminates at its inner end in a ring 13 the bore 14 of which is bell-mouthed so that it may be sprung tightly on to the end of the tube 1, which is tapered complementary to the taper of the bore 14, and when sprung into place the ring 13 covers the semi-circular slot 7 already mentioned. In order to hold the guard against inadvertent dislodgment the ring portion 13 is depressed at a point registering when in place with the tube wall depression 5 to form an internal projection 15 which engages the depression 5 when the ring 13 is assembled in position on the tube.

As already stated the socketed member 8 is rotatably mounted in the bore of the tube 1 and in order to maintain it against longitudinal movement it is provided intermediate its length with an annular groove 16 in which the projection 6 freely engages and this groove, when the member is in place, registers with the semi-circular slot 7, thus enabling a semi-circular plate 17 to be placed freely into both the slot and the groove so that the member 8 is held against movement longitudinally while at the same time being freely rotatable. The plate 17 is held in place by the ring 13 which covers it when the device is assembled and in order to permit the socket to be placed in the tube it is provided with a slot 39 through which the projection 6 passes as the socket is moved into place.

Secured concentrically into the inner end of the socketed member 8 and extending longitudinally throughout the length of the bore 2 of the tube 1 is a spiral bar 18 forming a screw member the opposite end of which extends between two oppositely arranged fingers 19 and 20 formed on one end of an inner tube 21 reciprocable longitudinally in the bore of the tube 1 and the diameter of which is such that it fits slidably the restricted bore 3 formed by the depressed groove 4. The spiral member 18 extends into the tube 21 and the outer ends of the fingers 19 and 20 are turned inwardly, as at 22 and 23, to engage freely the threads 110

of the spiral on opposite sides thereof, from which it will be apparent that reciprocation of the tube 21 rotates the spiral bar 18.

Immediately behind the fingers 19 and 20 5 the tube 21 is expressed so that an annular ridge 24 is formed which ridge contacts with, when the tube 21 is pulled outwardly to the end of its travel, the groove 4 formed by the depression 3 and prevents the tube 10 21 from being drawn out of the tube 1.

The tube 21 is provided on its outer end with a knob 25 and the outer end of the tube 1 is provided with a wire loop 26 capable of being swung to engage over the 15 knob when the tube 21 is at the end of its instroke to hold it against movement, while 27 indicates generally a cap adapted to cover the brush head when not in use, which cap consists of two semi-cylindrical shells 20 28 and 29 hinged to each other at one edge, as at 30, and provided with any suitable spring catch device 31 at their opposite edges so that when placed around the brush head the cap may be held closed until 25 it is desired to use it.

The brush member, indicated generally by the numeral 32, may be of any suitable form such as a plurality of cylindrical brushes of any approved design or material 30 mounted on and secured to the stem 10 so as to be rotatable therewith.

The manner in which the brush is used will be apparent. In use the cap 27 is removed and the brush member 32 held 35 against the teeth, the guard 12 being held by the fingers of one hand, whereupon the brush may be rotated by gripping the tube 21, which forms the operating handle, by the fingers of the other hand and moving 40 it back and forth longitudinally as long as is required.

What I claim as my invention is:—

1. A rotary toothbrush comprising a tube, a socket member rotatably mounted in one 45 end of said tube provided at its outer end with a brush and at its inner end with a spiral extending longitudinally within the tube, and a second tube reciprocatory within the first one provided with forwardly 50 extending oppositely arranged integral extensions, the extremities of which are rolled over inwardly and adapted to respectively engage the spiral on opposite sides thereof.

2. A rotary toothbrush comprising, a 55 tube having a semi-circular slot cut in its wall adjacent one end, a socketed member rotatably mounted in the slotted end of the tube provided at its outer end with a brush and at its inner end with a spiral extending 60 longitudinally within the tube, said socketed member having an annular groove registering with the said semi-circular slot, a semi-circular plate fitting freely both the slot and the groove maintaining the socketed member in rotatable position within 65 the tube, and a second tube reciprocatory

within the first-mentioned one having end fingers adapted to engage freely the spiral on opposite sides of the thread thereof.

3. A rotary toothbrush comprising, a 70 tube having a semi-circular slot cut in its wall adjacent one end, a socketed member rotatably mounted in the slotted end of the tube provided at its outer end with a brush and at its inner end with a spiral extending 75 longitudinally within the tube, said socketed member having an annular groove registering with the said semi-circular slot, a semi-circular plate fitting freely both the slot and the groove maintaining the socketed member in rotatable position within the tube, means for preventing inadvertent displacement of said plate, and a second tube reciprocatory within the first-mentioned 80 one having end fingers adapted to engage 85 freely the spiral on opposite sides of the thread thereof.

4. A rotary toothbrush comprising, a tube having a semi-circular slot cut in its wall on one side adjacent one end and a 90 depression in the opposite side providing an internal projection, a socketed member rotatably mounted in the slotted end of the tube provided at its outer end with a brush and at its inner end with a spiral 95 extending longitudinally within the tube, said socketed member having an annular groove registering with the said semi-circular slot and with which said internal projection engages, the said member being slotted to permit it to be passed over said projection when assembling, a semi-circular plate fitting freely both the slot and the groove, and a second tube reciprocatory 100 within the first-mentioned one having end fingers adapted to engage freely the spiral on opposite sides of the thread thereof.

5. A rotary toothbrush comprising, a tube having a semi-circular slot cut in its wall adjacent one end, a socketed member rotatably mounted in the slotted end of the tube provided at its outer end with a brush and at its inner end with a spiral extending 110 longitudinally within the tube, said socketed member having an annular groove registering with the said semi-circular slot, a semi-circular plate fitting freely both the slot and the groove maintaining the socketed member in rotatable position within the tube, means for preventing inadvertent 115 displacement of the said plate, a second tube reciprocatory within the first-mentioned one having end fingers adapted to engage freely the spiral on opposite sides of the thread thereof, and a cover for the 120 said brush comprising a pair of semi-cylindrical shells hinged together and adapted to enclose the brush when mounted on the end of the first-mentioned tube.

6. A rotary toothbrush comprising, a 130

tube having a semi-circular slot cut in its wall on one side adjacent one end and a depression in the opposite side providing an internal projection, a socketed member rotatably mounted in the slotted end of the tube provided at its outer end with a brush and at its inner end with a spiral extending longitudinally within the tube, said socketed member having an annular groove 10 registering with the said semi-circular slot and with which said internal projection engages, the said member being slotted to permit it to be passed over said projection when assembling, a semi-circular plate fitting freely both the slot and the groove, 15 a guard concave-convex both longitudinally and transversely adapted to partly surround the brush having its inner end formed as a ring adapted to engage the end of the tube when passed thereonto and 20 cover the said semi-circular plate, and a second tube reciprocatory within the first-mentioned one having end fingers adapted to engage freely the spiral on opposite sides of the thread thereof. 25

In testimony whereof I affix my signature at Vancouver, B. C., Canada, this 27 day of September, 1922.

JAMES ROBERT CRUIKSHANK.
